[57] **CLAIM**

The ornamental design for a tobacco water pipe, as shown and described.

DESCRIPTION

FIG. 1 is a perspective view from above of a tobacco water pipe showing my design;

FIG. 2 is a front elevational view thereof, with the tube portion broken away for convenience of illustration only;

FIG. 3 is a side elevational view thereof, the other side view being a mirror image of this view;

FIG. 4 is a rear elevational view thereof;

FIG. 5 is a top plan view thereof; and,

FIG. 6 is a bottom plan view thereof.
